UNITED STATES PATENT OFFICE.

ANGELO MAZZONI AND YONIKICHI FUJISHIN, OF BEAR CREEK, MONTANA.

STRAW DISPENSER.

Application filed May 1, 1925. Serial No. 27,235.

This invention relates to dispensing machines and more particularly to a novel device for dispensing soda straws one at a time.

The primary object of the present invention is to provide a novel device for dispensing soda straws, means being provided for permitting the convenient extracting of one straw at a time, without the fingering of the other straws.

10 Another object of the invention is to provide a soda straw dispensing device embodying a triangular shaped body in plan for receiving the straws having means for normally urging the straws toward the front converged end of the body and novel means actuated by the user of the device for lifting one straw at a time from the body through a suitable dispensing opening in the top of the body.

20 A further object of the invention is to provide a novel dispensing device for soda straws of the above character, which will be durable and efficient in use, one that will be simple and easy to manufacture and one 25 which can be placed upon the market at a small cost and present a pleasing appearance to the trade.

With these and other objects in view, the invention consists in the novel construction, 30 arrangement and formation of parts, as will be hereinafter more specifically described, claimed, and illustrated in the accompanying drawings, in which drawings:

Figure 1 is a front elevation of the improved device,

Figure 2 is a vertical section through the same showing the means for urging the straws toward the front converging end of the body,

40 Figure 3 is a central vertical section through the straw dispenser taken at right angles to Figure 2 illustrating the means for permitting the straws to be dispensed one at a time from the body,

45 Figure 4 is a horizontal section through the improved device taken on the line 4—4 of Figure 3,

Figure 5 is a top plan view of the device.

Referring to the drawings in detail, 50 wherein similar reference characters designate corresponding parts throughout the several views, the letter A generally indicates the improved straw dispenser, which comprises a body 10 of substantial triangular shape in cross section. The body 10 can

be formed of any desired material, such as sheet metal or the like and the same includes the rear wall 11, and the side walls 12, which gradually converge toward one another at the front of the body.

The walls 11 and 12 can be secured to or formed on the bottom wall 13 and the body is preferably enlarged at its lower end, as at 14 to provide a base so as to prevent the easy tipping over of the device.

A false bottom 15 is disposed within the body 10 and is arranged in spaced relation to the bottom wall 14 and at an angle thereto. By referring to Figure 3 of the drawings, it can be seen that the false bottom 15 is inclined downwardly toward the front end of the body. This false bottom conforms to the cross sectional configuration of the body 10, and owing to the inclination of the bottom 15, the straws tend to naturally 70 gravitate toward the converged end of the body.

In order to further urge the straws toward the front of the body, a follower plate 16 is provided, the lower edge of the follower plate is pivoted as at 17 to the rear wall 11 of the body, while the upper edge of the follower plate is adapted to engage the straws adjacent their upper ends for pushing the same toward the front of the body. An 80 opening 18 is formed in the false bottom 15 at the front end of the body and owing to the inclination of the side walls 12 of the body, the leading straw will be normally in alignment with the opening.

The upper end of the body is normally closed by a cover 19 which can be of any suitable shape to enhance the appearance of the device. As shown the lower end of the cover or cap is provided with a depending 90 flange 20 for engaging the walls of the body. A hinge 21 is employed for pivotally connecting the cover or cap to the front end of the body and the cover or cap adjacent to the hinge provided with an outlet opening 22 100 for the straws. This opening 22 is in substantial vertical alignment with the opening 18 and a flared guide shield 23 is placed around the opening 22 to facilitate the guiding of the straws dispensed through said opening. Any suitable means can be employed for holding or locking the cover or cap in its closed position and if preferred a hasp 24 and a staple 25 can be provided for that purpose.

It is to be noted that when the cover 19 is swung to its open position, that the entire upper end of the body is exposed which will permit the ready placing of the straws 5 to be dispensed in the body. The follower plate 16 can be held in its raised position during the initial placing of the straws in the body. If preferred, springs 26 can be coiled around the hinge pin for the follower plate for engaging the plate for normally urging the same in contact with the straws.

The means provided for dispensing one straw at a time from the body is of novel construction and forms an important part 15 of the present invention. As shown the extreme front of the body 10 is provided with an elongated guide casing 27 in which is slidably mounted a lifting rod 28. This rod 28 is mounted in suitable guides 29 carried 20 by the body and the casing 27 and the lifting rod is further guided in its sliding movement by the handle 30 which is connected to the upper end of the rod and which extends through an elongated guide slot 31 formed 25 in the front wall of the casing 27. The flared portion of the base 14 of the body 10 is provided with a slot 32 through which the lifting rod is adapted to extend and the front portion of the body is provided with 30 a slot 33 which is in alignment with the slot 32. The lower end of the lifting rod 28 is provided with a lifting hook 34 which is adapted to extend through the opening 18 in the false bottom 15. The upper end of 35 the hook is preferably pointed and is of a less size than the straws so as to permit the hook to ride into the same.

A contractile coil spring 35 is placed 40 around the lifting rod 28 and one end of the spring is anchored to the body 11, while the opposite end is anchored to the lifting rod.

In operation of the improved straw dispensing device, the straws are placed in the body through the open end thereof, as heretobefore described and when it is desired to remove a straw therefrom, the handle 30 is grasped and pulled upwardly. This will lift one of the straws through the opening 22, where the same can be readily grasped 45 and removed from the body. The handle 30 can now be released and the spring 35 will return the same to its normal position allowing another straw to be moved to the front of the body, when the same will fall 50 through the opening 18 and over the hook 34. The device can again be operated for removing another straw therefrom.

From the foregoing description, it can be seen that a novel soda straw dispensing device has been provided of an exceptionally simple and durable character, which will permit one straw at a time to be dispensed therefrom without the fingering of the other straws.

Changes in details may be made without

departing from the spirit or scope of this invention, but what we claim as new is:

1. A soda straw dispensing device comprising a body triangular shaped in plan, a false bottom disposed within the body arranged at an incline to the horizontal with its lowermost end facing the front end of the body, means normally urging the straws in the body toward the front end of the body, the upper end of the body being provided adjacent its forward end with a dispensing opening, and means for moving one straw at a time from the body through the opening.

2. A straw dispensing device comprising a body substantially triangular shaped in plan with its converged end disposed foremost, an inclined bottom wall arranged within the body having its lowermost end disposed at the converging end of the body, a cover for the upper end of the body provided adjacent its forward end with a dispensing opening, a lifting rod slidably associated with the front end of the body, and provided with a lifting hook, means normally holding the lifting rod in a lowered position beneath the bottom wall, the bottom wall being provided with an opening directly above the lifting hook, and means normally urging the straws toward the converged end of the body.

3. A soda straw dispensing device comprising a body, an enlarged hollow base formed on the lower end of the body, the body being substantially triangular shaped in plan with the converged end disposed foremost, a cover for the upper end of the body provided with a dispensing opening at the converged end of the body, an inclined supporting wall for the lower end of the straws provided with an opening arranged in direct alignment with the opening in the cover, the lower end of the supporting wall being disposed at the converged end of the body, a casing carried by the converged end of the body and provided with a vertical guide slot, a lifting rod slidably fitted within the casing, an operating handle for the upper end of the rod disposed in said slot, and a lifting hook formed on the lower end of the rod provided with a pointed terminal disposed directly beneath the opening.

4. In a soda straw dispensing device, a body substantially triangular shaped in cross section having its converged end disposed foremost, an enlarged hollow base formed on the lower end of the body, an inclined supporting plate for the straws extending downwardly from the rear wall of the body toward the front of the body and provided with an opening at its front end, a cover for the body provided with a dispensing opening at its front end in direct alignment with the first mentioned opening,

a flared guide carried by the cover and disposed about the last mentioned opening, a follower plate pivoted at its lower edge to the rear wall of the body for engaging straws adjacent to the upper end thereof, a guide casing carried by the front of the body provided with a vertical guide slot, a lifting rod slidably mounted within the casing, a lifting handle carried by the upper end 10 of the rod arranged in said slot, a lifting hook provided with a pointed terminal arranged in direct alinement with the opening in the supporting plate, and a contractile spring coiled about said lifting rod 15 having its opposite terminals secured respectively to the rod and to the body.

5. A soda straw dispensing device including a body substantially triangular-shaped in cross section having its converged end 20 disposed foremost, a false bottom disposed within the body and arranged at an incline to the horizontal with its lowermost end facing the front end of the body, spring means normally urging the straws in the 25 body toward the front end thereof, the upper end of the body being provided adjacent its forward end with a dispensing opening, means for moving one straw at a time from the body through the opening, and spring 30 means for automatically returning the moving means to its normal position.

6. A soda straw dispensing device comprising a body, an enlarged hollow base formed on the lower end of the body, an 35 inclined supporting plate immediately adjacent the upper end of the said base and provided with an opening therein, means

normally urging the straws in the body towards the opening in the supporting plate, the upper end of the body being provided with a dispensing opening, and a lifting rod slidably associated with the front end of the body and provided with a lifting hook normally disposed within the said base beneath the said opening in the plate, said hook adapted upon vertical movement of the lifting rod to engage one of said straws move the same from the body through the opening in the top thereof. 40 45 50

7. A soda straw dispensing device comprising a body, an enlarged hollow base formed on the lower end of the body, an inclined supporting plate immediately adjacent the upper end of the said base and provided with an opening therein, spring 55 means normally urging the straws in the body towards the opening in the supporting plate, the upper end of the body being provided with a dispensing opening, a lifting rod slidably associated with the front end 60 of the body and provided with a lifting hook normally disposed within the said base beneath the said opening in the plate, said hook adapted upon vertical movement of the lifting rod to engage one of said straws and move the same from the body through the opening in the top thereof and spring means for normally causing the lifting hook to return to its normal position beneath the 65 said supporting plate. 70

In testimony whereof we affix our signatures.

ANGELO MAZZONI.
